UNITED STATES PATENT OFFICE.

DAVIS MARINSKY, OF NEW YORK, N. Y.

TAPE.

1,160,925.

Specification of Letters Patent. Patented Nov. 16, 1915.

Application filed January 9, 1915. Serial No. 1,327.

To all whom it may concern:

Be it known that I, DAVIS MARINSKY, a citizen of the United States, and a resident of the city of New York, county of Bronx, 5 and State of New York, have invented a new and useful Improvement in Tapes, of which the following is a specification.

The object of my invention is to provide a tape with male and female parts of fasteners spaced at suitable intervals so that the two tapes may be held together on a garment, or otherwise, as desired. This object is accomplished by my invention, one embodiment of which is hereinafter set 15 forth.

For a more particular description of my invention, reference is to be had to the accompanying drawings, forming a part hereof, in which—

20 Figure 1 shows a tape provided with male members. Fig. 2 shows a tape provided with female members. Fig. 3 is a sectional view, taken on the line 3—3 of Fig. 4, looking in the direction of the arrows. Fig. 4 is a side elevation showing two tapes secured together according to my invention. Fig. 5 is a longitudinal section of the structure shown in Fig. 4. Fig. 6 shows a partially completed tape with eyelets therein 25 ready to receive a female member. Fig. 7 is a sectional view, taken on the line 7—7 of Fig. 5, looking in the direction of the arrows. Figs. 8, 9 and 10 are views showing the female and male members, the first two 30 being sectional views of the female member and the last an edge view of the male member.

Throughout the various views of the drawings, similar reference characters designate similar parts.

In the embodiment of my invention herein set forth, 1 indicates a tape for holding male members and 2 indicates a tape for-

holding female members. Each tape is folded on its medial line 3 and properly 45 stitched at 4, as indicated in Fig. 7. One side 5 of each tape is provided with a suitable metal eyelet 6 placed at suitable intervals. After the eyelets are in place, the tape 2 is folded and sewn at each edge, as 50 above set forth, and thereafter the female member 7 is placed in the eyelet 6 which is so formed that it binds against the same and fixes the female member in place.

The male member 8 is pressed through 55 each eyelet 6 of the tape 1 so that its head will project through the eyelet, and then the back of the tape is folded over and sewn so that the disk part of each male member 8 is sandwiched in between the two edges of 60 the tape, the tape being folded and sewn, as above described.

In the preferred embodiment of my invention, the eyelets are placed the same distance apart in each tape and uniformly 65 spaced so that the male and female members of the respective tapes will always register when the tapes are secured together by their respective fasteners.

While I have shown and described one 70 embodiment of my invention, it is obvious that it is not restricted thereto, but is broad enough to cover all structures that come within the scope of the annexed claim.

Having thus described my invention, 75 what I claim is—

In a device of the class described, two tapes one of which has a metal eyelet therein, a fastener with a female member fixed in this eyelet and a male member carried 80 by the other of said tapes so that the two tapes may be held together by said fastener.

DAVIS MARINSKY.
